UNITED STATES PATENT OFFICE.

JOHN G. GARLAND, OF HIGH POINT, NORTH CAROLINA, ASSIGNOR OF ONE-HALF TO
EMMET L. CROUCH AND ONE-HALF TO DAVID S. GURLY, BOTH OF HIGH POINT,
NORTH CAROLINA.

MAIL-BAG CATCHING AND DELIVERING MECHANISM.

1,115,657.

Specification of Letters Patent.

Patented Nov. 3, 1914.

Application filed June 21, 1913. Serial No. 775,046.

To all whom it may concern:

Be it known that I, JOHN G. GARLAND, citizen of the United States, residing at High Point, in the county of Guilford and 5 State of North Carolina, have invented certain new and useful Improvements in Mail-Bag Catching and Delivering Mechanism, of which the following is a specification.

This invention relates to mechanism for 10 automatically transferring mail bags or pouches from a moving train to a stationary support or vice versa.

The invention is designed as an improvement over an apparatus described and 15 claimed in my application filed Feb. 21, 1913 bearing Serial #749,915, and the primary object thereof is to provide means in the nature of a combination mail bag catching and mail bag releasing device wherein 20 the two coöperate in such a novel and peculiar manner as to automatically and effectually catch and support the mail bag or pouch and at the same time release and deliver a second bag or pouch, both operations 25 being effected simultaneously and both being controlled through the medium of a specially designed mail bag support or mechanism to be hereinafter fully described.

30 The invention still further contemplates the provision of means including a pair of spring controlled jaws or arms adapted to be arranged and fastened upon the mail bag support in a manner capable of receiving 35 the mail bag or pouch to be caught, the said bag when forced or drawn into engagement with the said jaws adapted to instantaneously actuate the spring means for automatically closing the jaws and locking or 40 fastening the mail bag therebetween.

A further object of the invention resides in the provision of means carried by the 45 said support and adapted to be simultaneously actuated during the receiving operation, whereby the second mail bag may be automatically released and delivered therefrom into a suitable receptacle or container provided therefor.

50 The above and additional objects are accomplished by such means as are illustrated in their preferred embodiment in the accompanying drawings, described in the following specification and then more particularly pointed out in the claims which are

appended hereto and form a part of this 55 application.

In describing my invention in detail reference will be had to the accompanying drawings wherein like characters denote like or corresponding parts throughout the 60 several views, and in which:—

Figure 1 is a perspective view illustrating the invention in connection with a car, showing the relative position of the several parts comprising my invention; Fig. 2 is a 65 similar view illustrating the position of the support as it appears in inoperative position; Fig. 3 is a plan view of the support; and Fig. 4 is a detail perspective view of the mail bag fastening means. 70

Referring now to the drawings, wherein is illustrated the preferred form of my invention the numeral 1 designates a mail car of the ordinary type having the usual door opening 2 in one side thereof through which 75 the mechanism comprising my invention is projected, the said mechanism being supported in operative position through the medium of blocks 3 disposed oppositely, one upon each side of the door 2, the said 80 blocks being connected by means of a longitudinally extending rod 4, the extremities of which are provided with heads 5 for effectually supporting the said rod against lateral or longitudinal movement independent 85 of the blocks 3 through which they extend.

The support means, designated in its entirety by the numeral 6 comprises a body portion 7 composed of a plate member having a recess or cut out portion 8 formed therein, the said plate member being pivotally and loosely mounted upon the rod 4. A handle 9 is formed integrally with the body portion 7 of the support for 95 swinging the latter into either operative or inoperative position; a hook member 10 being secured in any suitable manner to the side of the car 1 adapted to overlap or engage the handle 9 for effectually supporting 100 the support 6 in operative position as is shown to advantage in Fig. 1 of the drawings.

Clamping jaws or arms 11 are pivotally secured to the plate or body portion of the 105 support 6 within the recess 8 formed therein, one of the jaws terminating at its inner extremity in a head portion 12 having a

slot 13 formed therein, the said slot adapted to engage the fastening means designated in its entirety by the numeral 14 in a manner to be hereinafter fully described. An enlargement 15 is formed integrally with the said last mentioned jaw 11, the said enlargement having a pin 16 projecting from one face thereof, the provision of the pin permitting the jaws to be locked in open or spaced relation by means of a lever 17 pivoted as at 18 to the body 7 of the support, the said lever having a notch 19 formed therein for the reception of the pin 16 as illustrated in Fig. 1 of the drawings. A curved spring 20 is secured in any suitable manner to the body 7 of the support and extends over one end thereof so as to engage the enlargement 15 of one of the clamping jaws 11, this engagement between the spring and the said arm fastening or holding the latter within the notch 19 provided therefor, and, when withdrawn from engagement with the said notch causing the said two jaws to automatically close for effectually clamping and fastening the mail bag caught therebetween.

The head 12 of the jaw 11 having the slot 13 formed therein is adapted to register, when the jaws are in spaced relation, with a cut-out portion 21 formed within the body 7 of the support, the slot 13 embracing the fastening means 14 of the mail bag for locking the same within the said cut out portion, the said fastening means having a head 22 secured thereto which is adapted to engage the said head 12 for effectually supporting the mail bag in the desired manner.

A stationary support 23 is disposed at one side of the car 1, the support having a stationary arm 24 and a pivoted arm 25 secured thereto between which the mail bag to be caught is fastened, the center of the bag being disposed within the path of the support 6 when in projected or operative position, thereby causing the said bag to be forced between the jaws 11 of the support and into engagement with the pivoted lever 17 mounted thereupon. As the bag engages the lever 17, the latter is forced out of engagement with the pin 16 of one of the jaws thereby permitting the spring 20 to instantly close the said jaws and at the same time automatically release the fastening means 14 by withdrawing the slot 13 of the head 12 from engagement with the fastening means 14 of the mail bag or pouch to be released or delivered, this action of the jaws 11 fastening and catching the first mentioned mail bag between the jaws 11 of the support and permitting the last mentioned mail bag to be released and delivered into the suitable receptacle provided therefor (not shown) along the siding.

65 By curving the jaws 11 as illustrated in

Fig. 3 of the drawings it will be seen that the tension of the spring 20 upon the enlargement 15 of one of the jaws will cause the same to open and close simultaneously, and that by forcing the pin 16 into engagement with the notch 19 of the pivoted lever 17, the clamping jaws 11 are locked or fastened in open and spaced relation and in a manner capable of receiving the mail bag to be caught therebetween. ⁷⁵

It will be further seen from the above, taken in connection with the accompanying drawings that the mail bag or pouch to be acted upon is automatically and simultaneously received and released by the co-operation of the several embodiments comprising the support 6 of my device; that by pivotally mounting the support upon the rod 14 extending transversely of the doorway 2, the said support may be swung into operative or inoperative position by withdrawing the handle 9 from engagement with the hook member 10 provided therefor; and that the means employed for supporting and fastening the mail pouch or bag upon the support member is of such construction as to be automatically and simultaneously released with the receiving or catching of the mail bag by the clamping jaws 11 of the support. ⁸⁰

In reduction to practice, I have found that the form of my invention, illustrated in the drawings and referred to in the above description, as the preferred embodiment is the most efficient and practical; yet realizing that the conditions concurrent with the adoption of my device will necessarily vary, I desire to emphasize the fact that various minor changes in details of construction, proportion and arrangement of parts may be resorted to, when required, ⁸⁵ without sacrificing any of the advantages of my invention, as defined in the appended claims. ⁹⁰

Having thus fully described my invention, what I claim as new and desire to secure by Letters Patent, is: ⁹⁵

1. A mail transferring device bodily movable into and out of an operative position, said device comprising a stationary jaw, a relatively movable spring actuated jaw, ¹⁰⁰ support means for the respective jaws, support means for the mail bag comprising a notched extension integral with the movable jaw, said extension adapted to traverse a notch formed within the said support, ¹⁰⁵ a notched arm pivoted to the support, and a pin upon the movable jaw engageable with one notch in the arm to maintain the jaws separated and against tension of the spring means, said arm being movable to release the movable jaw through engagement of the mail bag to be transferred therewith, as and for the purpose set forth. ¹¹⁰

2. In a mail bag transferring mechanism, ¹¹⁵

the combination of a pivotally supported body portion having a cut out portion formed therein, a pair of spring actuated pivotally mounted gripping jaws secured 5 to the said body portion, the said jaws being disposed in the path of the mail bag acted upon, a slotted head formed integrally with one of the said jaws adapted to register with the said cut out portion for fastening a 10 mail bag suspended from the said body portion, and a lever pivotally secured to the said body portion adapted to engage one of the said jaws for retaining the jaws in spaced relation, the engagement between the 15 mail bag acted upon and the said lever adapted to simultaneously close the jaws and fasten the mail bag acted upon therebetween and release the mail bag suspended from the said body portion, as and for the 20 purpose set forth.

3. In a mail bag transferring mechanism, the combination of a pivotally supported body portion, means for retaining the said body portion in operative position, pivotally 25 mounted gripping jaws secured to the said body portion, the said jaws being disposed in the path of the mail bag to be acted upon,

a head formed integrally with one of the said jaws adapted to register with a cut out portion formed within the said body portion, 30 a slot in the head supporting a bag suspended from the said body portion, a lever pivotally secured to the said body portion having a notch formed therein, a pin projecting from one of the said jaws adapted 35 to be engaged by the said notch for retaining the jaws in spaced relation, a spring secured on the body portion adapted to engage one of the said jaws for automatically closing the said jaws when the pin is withdrawn 40 from engagement with the said notch, the engagement between the mail bag acted upon and the said lever adapted to simultaneously close the jaws and withdraw the slotted head from engagement with the 45 mail bag suspended from the said body portion, as and for the purpose set forth.

In testimony whereof I affix my signature in presence of two witnesses.

JOHN G. GARLAND.
